COIN AND SLUG SEPARATING DEVICE

William Patzer and Walter A. Tratsch,
Chicago, Ill.

Application March 16, 1936, Serial No. 69,147

6 Claims. (Cl. 194—101)

This invention relates to a coin and slug separating device.

It is an object of this invention to provide an improved coin and slug separating device which is relatively simple and inexpensive in construction and efficient in use.

Another object of the present invention is to provide a new and improved coin and slug separating device for preventing fraudulent coins, tokens, slugs, etc., from entering into or operating a coin-operated machine or apparatus with which the new coin and slug separating device is associated.

Another object of the present invention is to provide a new and improved device for preventing a magnetically attractive or steel slug from entering into or operating the machine or apparatus with which the new coin and slug separating device is associated.

An additional object of the invention is to provide a new and improved device for ejecting a magnetically attractive or steel slug out of the coin chute, which is embodied in and forms a part of the new coin and slug separating device, and into a discharge chute which is associated with the same.

A further object of the present invention is to provide a new and improved device for preventing a fraudulent and relatively light slug, such, for example, as a paper or cardboard disc, from operating a machine, apparatus or the like with which the new selecting device is associated.

Still another object of the present invention is to provide a novel device for ejecting a relatively light slug, such for example, as a paper or cardboard disc, or the like, out of the coin chute, which is embodied in the new device, and into a discharge outlet which is provided in the same.

Another and important object of the present invention is to provide a novel device for effecting a selection between fraudulent slugs or tokens, such as brass, copper, lead, zinc, and aluminum slugs or discs, and a coin having the intended and proper metallic composition, such as a nickel, dime, quarter or the like.

A further object of the present invention is to provide a novel device for effecting a separation between fraudulent slugs or tokens, such as brass, copper, aluminum, lead and zinc slugs and the like, and a coin having the intended or proper composition, such as a nickel, dime, quarter, or the like, whereby the fraudulent slugs will be discharged or diverted from the coin chute of the device onto a discharge outlet pro-

vided therefor, in the device, and the coin having the proper and intended metallic composition will be discharged from the coin chute into another discharge outlet which is provided in the device for the reception of the same.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is an elevational view showing a preferred form of the new coin and slug separating device;

Fig. 2 is a view on line 2—2 in Fig. 1, partly in section and partly in elevation;

Fig. 3 is a fragmentary elevational view on line 3—3 in Fig. 2;

Fig. 4 is a vertical sectional view on line 4—4 in Fig. 3;

Fig. 5 is a vertical sectional view, on line 5—5 in Fig. 2, showing the coin chute and the several selecting or separating devices embodied in the invention;

Fig. 6 is a sectional view on line 6—6 in Fig. 1 showing the permanent stationary magnet embodied in the new device for creating eddy currents in the coin chute;

Fig. 7 is a sectional view on line 7—7 in Fig. 2 showing part of the discharge chute for steel and paper slugs and the like; and

Fig. 8 is a bottom plan view of the new coin and token selecting device, on line 8—8 in Fig. 1.

A preferred embodiment of the new coin and token selecting device is shown in the drawings, is therein generally indicated at 10, and comprises a body 11 in which is formed a tortuous coin chute, which is generally indicated at 12. Formed in the body 11 are two inlets 13 and 14 40 to the coin chute 12, the inlet 13 opening upwardly or vertically and the inlet 14 opening laterally or horizontally so that coins or tokens may be inserted into the coin chute 12 either from above or from the side of the same.

The coin chute 12 includes an inclined upper portion 15 (Fig. 5) and formed in one wall 16 of this portion 15 of the coin chute 12 is a slot or opening 17.

Pivottally mounted, as at 18 (Fig. 4), upon the body 11 of the new selecting device is a magnet carrier 19 and mounted on and carried by this member 19 is a bar magnet 20, one edge of which projects through the slot or opening 17 which is formed in the wall 16 of the upper portion 55

15 of the coin chute 12, for a purpose to be described presently.

The magnet carrier 19 comprises a pair of plates 19a and 19b (Figs. 3 and 4) each having 5 an elongated opening the same length as, but of less width than, the magnet 20. The outer plate 19b is provided with spaced slots which fit onto a pair of spaced hooks 19c formed on the larger plate 19b, and the smaller outer plate 19a having means such as the screw 19d clamping the plates together on that side of the magnet 20 opposite the hooks 19c, whereby the magnet is firmly clamped with its inner edge portion 21 exposed through the opening 17 in the chute.

15 The pivoted magnet carrier 19 has an offset arm 22 (Figs. 3 and 4) and projecting into a position between the body 11 of the coin chute and the arm 22 of the magnet carrier 19 is a pin 33 which is carried by an operating lever 32. This operating lever 32 is pivotally mounted, between its ends, 20 as at 31, upon the body 11 of the device.

Pivoted on the body 11 of the new device, as at 25, (Fig. 2), is an operating lever 24 and this operating lever 24 carries a pin 23. This 25 pin or extension 23 of the lever 24 projects between a member 34 and an offset arm 35 of the latter (Fig. 4) and the member 34 forms one wall of the upper portion 16 of the coin chute 12 and is pivotally mounted upon the body 11 of the device, 30 as at 18 (Figs. 1 and 4).

The lever 32 has a lower end portion 26 which is engageable with the inner end portion 27 of an actuating member or plunger 28 which is slidably mounted in a support 29 which forms one wall of 35 the cabinet of the coin-controlled machine or apparatus, with which the new device is associated, this actuating member or plunger 28 being normally urged into its initial position (as in full lines, Fig. 2) by means of a resetting coil spring 30 which is arranged thereon.

Attached to the body 11 of the coin chute 12, at one side thereof, (Figs. 4 and 7) is a member 37 and this member 37 cooperates with the body 11 of the device to form a discharge chute 38 for 45 magnetically attractive or steel slugs, and also for relatively light slugs such as paper, and cardboard slugs and the like, as will be described hereinafter.

Provided in the coin chute 12, at the lower end 50 of upper portion 16 thereof (Fig. 5) is a deflector 39, the purpose of which will be explained herein-after, and formed in the bottom wall 40 of the coin chute 12, adjacent the deflector 39, is a recess or pocket 66 (Fig. 5) which leads from the coin chute 12 into the discharge chute 38.

The coin chute 12 includes a portion 41 (Fig. 5) which is inclined in a direction which is opposite to the inclination of the upper portion 16 of the same, and pivotally mounted in the coin chute 12, 60 at the entrance to the portion 41 thereof, as at 42, is a gate 43 by means of which relatively light slugs such, for example, as cardboard and paper discs, will be deflected back into the pocket or opening 66, and thence into the discharge chute 65 38, in a manner which will be described herein-after.

The coin chute 12 also includes a portion 44 (Fig. 5) which extends substantially parallel to the upper portion 16 of the same and at an angle 70 relative to the portion 41. The coin chute 12 also includes a lower portion 45 which extends in an opposite direction relative to the inclination of the portion 44 of the same and at its lower 75 end this portion 45 of the coin chute is enlarged

and bifurcated or divided so as to form two diverging branches or discharge outlets 46 and 47.

Pivoted, as at 48, in the lowermost portion 45 of the coin chute 12, between the branches or discharge outlets 46 and 47 of the 5 same is a deflector 49. This deflector has a relatively sharp-pointed upwardly extending projection or nose portion 50 and this deflector 49 is adjustable about its pivot 48 by means of a screw and slot connection 51-52 with the side wall 53 of the lowermost portion 45 of the coin chute 12.

Likewise pivotally mounted in the lowermost portion 44 of the coin chute 12, as at 54, (Fig. 5) but above the deflector 49, is a second deflector 55 and this deflector 55 has a screw and slot connection 56-57 with the side wall 53 of the lowermost portion 45 of the coin chute 12. This deflector 55 has a pointed projection 62, the purpose of which will be explained hereinafter.

Mounted upon opposite sides of the body 11 of the device between the upper and lower ends of the lowermost portion 45 of the coin chute 12, is a pair of permanent magnets generally indicated at 58. These magnets are preferably of the horseshoe type and includes a magnet 59 which is 23 arranged on one side of the lowermost portion 45 of the coin chute 12 and a complementary magnet 60 which is arranged on the opposite side of the same.

Operation

30

If a magnetically attractive disc or token is inserted into the coin chute 12, through either of the two inlets 13 and 14 thereto, (Fig. 5) it will travel by gravity down the uppermost portion 16 of the coin chute 12, along the bottom wall 61 of 33 the same, until it comes opposite to or into alignment with the slot or opening 17, whereupon it will be attracted by a portion 21 of the magnet 20 and will be held thereby in the uppermost portion 16 of the coin chute 12 and against traveling farther down the same, and the thus held magnetically attractive or steel disc or slug will be held in this position (as at A, Fig. 5) until the plunger 28 is operated, as will now be described.

In order to release the thus held magnetically attractive or steel slug from the uppermost portion 16 of the coin chute 12, and so as to clear the latter for the passage of the intended or proper coin, the operator of the device pushes in on the plunger 28 (right to left, Fig. 2). When the plunger 28 is thus pushed in, its inner end portion or head 27 engages the lower end portion 26 of the lever 24 and thereby pivots the latter, at 25 (clockwise, from full to dotted line position, Fig. 2). When the operating lever 26 is thus pivoted (clockwise, from full to dotted line position, Fig. 2), lever 32 pivots in an opposite direction and the lateral extension or pin 33 carried thereby engages the offset arm 22 of the magnet carrier 19 and thereby pivots the latter, at 18, (counter-clockwise, from full to dotted line position, Fig. 4), thereby moving the magnetic portion 21 away from the uppermost portion 16 of the coin chute 12 and away from the slot or opening 17 which is formed in the latter, thereby releasing the magnetically attractive or steel slug from the position in which it is held, at A, Fig. 5, whereupon the thus released magnetically attractive or steel slug will fall into the discharge chute 38 (Figs. 4 70 and 7), since the movable side wall closure 34 has likewise been pivoted outwardly to open up the chute passage and permit the released coin to move sidewise out of the same. This pivotal movement occurs when arm 26 pivots so as to 75

cause the lateral pin 23 thereof to bear against the extension 35 and urge closure 34 outwardly.

More specifically, when the plunger 28 is pushed in (right to left, Fig. 2) and thereby pivots the lever 26, at 25 (clockwise, from full to dotted line position, Fig. 2) the arm 63 of the lever 26 engages the arm 64 of the lever 32, thereby pivoting the latter, at 31 (counterclockwise, from full to dotted line position, Fig. 2). During this 10 movement of the lever 32 the lateral extension 33 thereof engages the offset arm 32 of the carrier member 19 and thereby pivots the latter, at 18 (counterclockwise, from full to dotted line position, Fig. 4), thereby withdrawing the 15 magnet 20 from the slot 17, whereupon the magnetically attractive or steel slug which was previously held in the uppermost portion 16 of the coin chute 12, by the magnet 20, will drop, by gravity, out of the latter and off from the bottom 20 wall 61 of the same (as indicated at 65, Fig. 4) into the discharge chute 38, and in this manner a magnetically attractive or steel slug is ejected from the coin chute 12 and is prevented from traveling down the latter into the discharge outlet 47 through which the intended and proper 25 coin or token must be discharged in order to operate the machine or apparatus with which the new device is associated.

When the plunger 28 is released, the magnet 30 carrier 19 and the member 34 will pivot, by gravity, back into their initial positions (as in full lines, Fig. 4).

If a relatively light slug or disc, such as a paper or cardboard disc or the like, is inserted into the 35 coin chute 12 through either of the inlets 13 and 14 thereto, it will roll by gravity down the bottom wall 61 of the uppermost portion 16 of the coin chute 12 and will roll off from the said bottom wall 61 of the portion 16 of the coin chute 12 onto the deflector 39 by which it will be deflected, along the dotted line path B, Fig. 5, against the pivoted gate 43, from which it will be deflected or will rebound downwardly into the pocket or opening 66 (Fig. 5) whence it will fall 40 into the discharge chute 38, and in this manner a relatively light slug or disc, such as a cardboard or paper slug will be prevented from passing down the coin chute 12 into the discharge outlet 47 for the intended and proper coin.

If a coin or token of the intended and proper size and metallic composition, for example, as a nickel, is inserted into the coin chute 12, through either of the two inlets 13 and 14 thereto, the said coin will travel by gravity down the uppermost portion 16 of the coin chute 12, and will strike the deflector 39 by which it will be deflected, along the path of the full line arrows C, Fig. 5, against the gate 43, thereby pivoting the latter at 43, (clockwise, from full to dotted line position, (Fig. 5). The intended and proper coin, being heavier than a relatively light disc or slug such as a cardboard or paper disc, will thus pivot the gate 43 into open position and will pass by the same, whereupon it will continue down the portion 44 of the coin chute 12 and into the lowermost portion 45 of the same.

As the coin having the intended and proper metallic composition passes down the lowermost portion 45 of the coin chute 12 it will be retarded or slowed up only slightly by the eddy currents set up in the lowermost portion 45 of the coin chute 12, and hence will drop out of the lowermost portion 45 of the coin chute 12 onto the upright point or projection 50 of the deflector 49, from which it will travel (along the path D,

indicated by full line arrows, Fig. 5) into the discharge outlet 47. It is to be noted at this point, that the eddy currents set up in a coin moving down the lowermost portion 45 of the coin chute 12, through the field of the magnets 58, will retard or slow up only slightly a coin which has the intended and proper metallic composition such, for example, as a nickel, as the latter runs down the lowermost portion 45 of the coin chute 12, and hence the intended and proper coin will have sufficient momentum, when it leaves the lowermost portion 45 of the coin chute 12, to move past the point 50 of the deflector 49 and into the discharge outlet 47 of the coin chute 12.

However, if a fraudulent coin or token, which is made of a metal or alloy different from that of the intended coin, such for example, as lead, brass, zinc, or copper and aluminum slugs, is inserted into the coin chute 12 it will travel by gravity down the latter, in the manner hereinbefore described relative to the intended coin and will, as it passes through the lowermost portion 45 of the coin chute 12, be slowed up slightly by the eddy currents which are set up therein by the magnet 58 so that when the said fraudulent coin or token emerges from the lowermost portion 45 of the coin chute 12 it will not have sufficient momentum to move past the deflector 49-50 into the discharge outlet 47 for the intended 20 coin and hence will follow the dotted line path E, Fig. 5; and as the said fraudulent coin or token follows this path E it will drop down onto the point 50 of the deflector 49, and it will engage the projection 50 of the deflector 49 at one 25 side of its vertical center and will be deflected thereby into the discharge outlet 46. In this manner a fraudulent coin or token which is composed of a metal or alloy which is different from the metallic composition of the intended and 30 proper coin is prevented from traveling from the coin chute 12 into the discharge outlet 47 of the same and is directed into the discharge outlet 46.

In the event that the metal used in the fraudulent slug is less affected by the eddy currents set up by the magnet 58 than is the metal of the intended and proper coin it will, upon emerging from the lowermost portion 45 of the coin chute 12, have more momentum than the intended and 45 proper coin and hence will strike the point 62 of the deflector 55 by which it will be deflected along the dotted line path F, Fig. 5, into the discharge outlet 46.

It is to be noted, in this connection, that when 55 the metal of the intended coin, such, for example, as silver, is affected to a greater extent by the eddy currents, resulting from passage through the field of the magnets 58, than is the metal of which the fraudulent slugs are composed, then, in 60 that event, the foregoing arrangement of the outlets 46 and 47, Fig. 5, and which arrangement is specifically designed for a nickel coin chute, must be reversed so that the intended coins will fall into the discharge outlet 46 and the fraudulent slugs will fall into the outlet 47, since in 65 this event the intended coins will be slowed up more by the eddy currents of the magnet 58 than the metal slugs will be, and hence the intended coins will fall into the discharge outlet 46 and the 70 metal slugs will fall into the discharge outlet 47.

It will be noted (Fig. 5) that the deflectors 55 and 49 may be adjusted, by means of their screw and slot connections 56-57 and 51-52, respectively, so as to compensate the deflectors 75

for wear upon the points 62 and 58, respectively, thereof, and to compensate the deflectors for loss of strength by and in the magnet 58 and resulting changes in the strength of the field set up thereby across the lowermost portion 45 of the coin chute 12.

It is also to be noted, in connection with the present device, that if an attempt is made to operate the same fraudulently, by tipping the device out of its normal and proper operating position (counterclockwise, Fig. 5) the fraudulent slug will acquire so much momentum, as it travels down the lowermost portion 45 of the coin chute 12, that it will engage the deflector 55 and will be deflected therefrom downwardly into the discharge outlet 46.

While we have illustrated and described the preferred form of construction for carrying our invention into effect, this is capable of variation and modification, without departing from the spirit of the invention. We, therefore, do not wish to be limited to the precise details of construction set forth, but desire to avail ourselves of such variations and modifications as come within the scope of the appended claims.

Having thus described our invention, what we claim as new and desire to protect by Letters Patent is:

1. A coin chute including a substantially flat body providing a descending chute passage having a sidewise drop-out opening in one wall portion thereof and pivoted gate means normally closing said opening, magnetic means carried by a pivoted member mounted on the wall of said chute opposite said gate means and normally positioning a magnet member close to said passage, together with lever mechanism for moving both said gate means and pivoted member laterally of the chute body, said mechanism including a pair of levers pivotally mounted at an edge of said body for movement in a plane normal thereto, one of said levers having a yoke-like cam formation and the other said lever having a cam finger receivable in said cam formation whereby said levers are interconnected for joint movement, said levers respectively having operative connection with said gate means and pivoted member to move the same laterally as aforesaid responsive to movement of one of said levers.

2. In a device of the class described, means providing a descending coin passage having an elongated slit in a side wall thereof and extending in a general direction of the passage, said passage having a discharge opening extending substantially the length of said slit in a wall of the passage opposite thereto, gate means mounted for movement toward and away from said passage to open and close the latter, a magnet carrier mounted for movement toward and away from said slit, mechanism for moving said gate and said magnet carrier jointly in a direction away from said passage, and an elongated magnet formed with a longitudinally extensive edge connecting opposite polar extremities thereof and mounted on said carrier so that said edge will fit closely in the slit in close proximity to said passage and coins moving therein but out of physical contact with said coins when said carrier is moved toward said passage, said gate and magnet carrier being arranged and constructed normally to move by gravity toward said passage.

3. In a device of the class described, means

providing a descending coin passage having a discharge opening between its ends and a drop-out opening at a lower level than said discharge opening together with rebound means positioned in said passage for engagement by a coin to effect rebound of certain coins past said drop-out opening for continued movement toward the end of the passage, and testing means including an elongated magnet of a length greater than the diameter of the largest coin element to be deposited in said device and mounted for movement toward and away from said passage opposite said discharge opening with the long axis of the magnet extending in the direction of movement of coins in said passage, closure means normally closing said discharge opening, and mechanism for simultaneously opening said closure means and moving said magnet away from said passage to effect release of magnetically attracted coin elements, said elements tending to be discharged through said discharge opening or said drop-out opening.

4. The device of claim 3 in which said passage is provided with an elongated slit in a wall portion thereof opposite said discharge opening, said magnet being further characterized by the provision therein of an elongated edge portion fitted into said slit so as to lie in close proximity to said passage for attracting magnetically permeable coin elements and setting up eddy currents in metallic coin elements passing said magnet when the same is positioned close to the passage.

5. In a device of the class described, a body providing a coin passage and testing means including a pair of plate members having elongated registered openings therein and clamped together with an elongated magnet of greater width than said openings and seated in the latter so as to be clamped between said plates with a longitudinally extensive portion of said magnet projecting laterally through said openings beyond the plane of a particular one of said plates, said particular plate being pivotally mounted on said body for movement toward and away from said passage whereby to position said projecting portion of the magnet in close proximity to the passage, said plates being engaged on one side of said magnet by hook and slot formations and being provided with means urging the plate members together on the opposite side of said magnet.

6. In a device of the class described including a body providing a coin passage having an entrance and an exit end, testing means including a pair of plate members having elongated registered slots therein, an elongated bar magnet clamped between said plates in said slots and having an edge portion lying between its polar extremities exposed substantially beyond the plane of one of said plates, said clamp plates being movably mounted on said body to dispose said edge of the magnet against the latter so as to extend substantially in the direction of said passage, said body having an elongated slit adapted to register with said edge portion of the magnet, said clamp plate members being arranged normally to dispose said edge of the magnet in register with said slit, and means for moving said plate members to withdraw said edge from said slit.

WILLIAM PATZER.
WALTER A. TRATSCH.
